UNITED STATES PATENT OFFICE.

WILLIAM M. BARNES, OF PHILADELPHIA, PENNSYLVANIA.

IRONING-MACHINE.

SPECIFICATION forming part of Letters Patent No. 731,267, dated June 16, 1903.

Application filed December 29, 1902. Serial No. 136,879. (No model.)

To all whom it may concern:

Be it known that I, WILLIAM M. BARNES, a citizen of the United States, residing at Philadelphia, county of Philadelphia and State of Pennsylvania, have invented a new and useful Improvement in Ironing-Machines, of which the following is a full, clear, and exact description, reference being had to the accompanying drawings, which form a part of this specification.

My invention relates to certain improvements in that class of ironing-machines in which the article to be ironed is placed upon a flat ironing-table, which is moved against a flat heated ironing-plate.

I will first describe the embodiment of my invention as illustrated in the accompanying drawings and then specifically point out the invention in the claims.

20 Figure 1 is a front elevation of an ironing-machine embodying my invention. Fig. 2 is a plan view on line 2 2, Fig. 1. Fig. 3 is a vertical section through toggle mechanism. Fig. 4 is an enlarged plan view of locking-handle with table removed. Fig. 5 is a sectional detail of upright *a*, bearing *b*, and arm *B*.

A is the base of the machine, having the vertical extensions *a*³ *a*³. *a a* are uprights secured to these vertical extensions *a*³ *a*³.

30 Sleeved upon each of the uprights *a a* is the sleeve *b* for the arm *B*. The sleeves *b* are cut away at their central portions, so that the length of contact or bearing of the sleeve *b* with the upright *a* is less than the length of the sleeve *b*. The ironing-table *C* is secured to the arm *B* and is a flat plate, preferably having upon it a felt or other soft yielding cover. The garment to be ironed is secured upon this table at one end by the clamp *C'* and 40 to the roller *C*² at the other end. Beneath the ironing-table *C* and secured to the arm *B* is the shield *c*, having the upturned ends *c'* extending beyond the sides of the ironing-table, so as to properly hold and protect any projecting portions of a garment upon the ironing-table. There is one of these arms *B* sleeved upon each upright *a*, and each arm carries a corresponding ironing-table.

45 *D* is the lower leg, and *D'* the upper leg of 50 a toggle, the two legs being pivoted together at

d, the lower leg *D* being pivotally attached to the base *A* and the upper leg *D'* to a block *E*.

*C*³ is a wedge having the ribbed lower portion *e'* running on this block and also having the extension *e*² surrounding a rod having the threaded end *e*³ and turning-handle *e*⁴. The threaded end *e*³ of the rod enters the block *E*. The block *E* is carried by the cross-bar *F*, having at its outer ends the rollers *f*, which rest and travel upon the guides *f'* on the face 60 of the vertical extensions *a*³ *a*³.

G is an internally-threaded block, having the extension *g*, provided with the vertical slot *g'*, in which slot rests the pin *d*, forming the pivotal connection of the two legs of the toggle. 65

H is a shaft having the threaded end *h*, working in the threaded block *G*. This shaft has the bracket-bearings *h' h'* from each side of one of the vertical extensions *a*³, and in the spaces between these brackets *h'* and the vertical extension are placed the thrust-bearings *h*² *h*², preferably having ends formed of fibrous material. On the end of this shaft are the loose pulleys *I I'* and the fast intermediate pulley *J*, the pulley *I* being operated 75 by a cross-belt and the pulley *I'* by a straight belt from a proper source of power.

K is the belt-shifter, having the belt-holders *k k'*. *L* is the belt-shifting, rod which is connected to the belt-shifter in the following 80 manner:

l is a block having an orifice in which enters the belt-shifter, the belt-shifter being secured thereto by the set-screw *l'*. The block *l* has also an orifice in which the end of rod *L* enters 85 and is secured by means of set-screw *l*². By this arrangement the position of block *l* may readily be adjusted. This rod *L* is pivoted to the link *l*³, pivoted to a projection from the bracket *h'*. 90

M is a rod connected to link *l*³ and passing through a slot in the extension *M'* from the block *G*. Fixed upon the rod *M* is a stop *M*².

m is a second rod, secured to the rod *M* and passing through an orifice *m*³ in the central portion of upper toggle-leg *D'* and having beyond said central portion the fixed stop *m*⁴. 95

o is a block on the shifting-rod *L*, having a rod *l* extending therefrom.

*a*⁷ is a bracket extending from the vertical 100

extension a^3 , having the rod 2 extending therefrom.

O is a hand-lever pivotally connected to the rods 1 and 2. Surrounding the rods 1 and 2 are the springs o' , contacting with the lever O.

o^2 represents nuts on the rods 1 and 2. By turning the nuts the proper compression to hold the rod from movement by jarring in any position may be obtained.

10 Pivoted to the under surface of each arm B is a disk P, having the handle p and the pins $p' p^2$. To the pin p' is connected one end of a coil-spring Q. The other end of the coil-spring Q is secured to the fixed pin q , secured to the 15 arm B. Projecting from the disk P is the hook S. Upon the cross-bar F on each side of the block E is a projection R. When either arm, with its carried table, is brought over the toggle-lever to the position shown in Fig. 1, 20 the handle p of that table is operated, bringing the hook around the corresponding projection R, where it is held by the spring Q, the pin p' limiting the movement of the handle and disk by striking the arm B. When it is desired 25 to move the table away, the handle p is operated, moving the disk until the pin p^2 strikes the arm B, when any further pressure upon the handle will swing the table. Thus this arrangement provides both a locking and moving 30 device for the table.

Fixedly secured to the uprights $a a$ is the cross-frame T, holding central of the machine the ironing-plate T', which is heated in any well-known manner. Secured to this plate so 35 as to be in parallel relation with the ironing-table when lifted against the ironing-plate, as will hereinafter be described, is the scale-plate V.

The operation of the machine is as follows: 40 Whichever ironing-table is to be operated is swung by means of the handle p until the end of the arm B is in line with the wedge. The straight belt is then thrown on and the screw pulls the block so as to elevate the toggle mechanism, elevating the table against the ironing-plate. When the toggle mechanism rises sufficiently, the extension M' strikes the stop m^2 , moving the belt onto the idle pulley. 45 The hand-lever O is operated to bring the cross-belt into action, which moves the screw to bring the toggle mechanism down, moving the table down from the plate. In the downward movement of the toggle when the toggle-leg D' strikes the stop m^4 the cross-belt is shifted 50 to the idle pulley. The arrangement of levers and stops is such that in the upward movement of the toggle the shifting of the belt is rapid, while in the downward movement the shift is slower. As may be seen, the extension or stop M' is connected to the toggle-leg 55 D' at its greatest radial point—that is, the point most remote from its pivot. The stop m^2 is also so arranged that the stop or projection M' strikes it at the time when the ironing-table is brought against the ironing-plate with the desired pressure. The long radius of the

toggle-leg D' will thereafter for any movement of the toggle-leg very rapidly shift the belt. As a consequence the power in the upstroke can be left on until the very last moment, 70 thus producing the maximum power when ironing upon the ironing-plate. In the descent of the toggle, as may be seen, the position of the stop m^4 is such that it is struck by the toggle at a point intermediate between its pivot 75 and end. As a consequence, its radial action is much shorter, and consequently a longer period is taken to shift the belt on the down-stroke than on the upstroke. The belt being moved gradually, the adjustment is made so 80 that it is completely shifted as the toggle reaches its most downward position, and the driving-pulley is prevented from having any momentum, which might occur were the shift on this movement made rapidly. 85

The purpose of having the bearing for sleeve b less than the length of the sleeve is to prevent any spring tendency of the sleeve b causing any binding of the sleeve or bearing.

The purpose of the scale upon the ironing-plate, hereinbefore described, is as follows: 90 In order to properly iron the lower ply of an open-bosom shirt at the double-ply portion of the bosom, there has been invented the use of a plate inserted at this point between the 95 folds or plies. As bosoms of shirts vary considerably in length, it often requires considerable time to determine the proper length of plate to be inserted therein. By preliminarily bringing the ironing-table up to the ironing-plate, the length of bosom, and thus the 100 size of plate required, may readily be determined and the proper plate inserted from a series of plates X, hanging upon pegs x at the side of the machine. 105

So much of the hereinbefore-described machine as comprises the adjustable connection between the belt-shifting rod and the belt-shifter and the shifting-lever connected to the belt-shifting rod and its connection and 110 operation I do not claim herein, as the same forms the subject-matter of a divisional application filed by me February 12, 1903, Serial No. 143,045.

Having now fully described my invention, 115 what I claim, and desire to protect by Letters Patent, is—

1. In a machine of the character described, the combination of an ironing-plate and two uprights upon opposite sides of the ironing-plate, an ironing-table sleeved upon each of 120 said uprights, so as to move vertically and laterally and a centrally-disposed lifting mechanism, the tables being sleeved respectively to swing from opposite sides into alignment with said lifting mechanism.

2. In a machine of the character described, the combination of an ironing-plate, an ironing-table movable to and from alignment with 125 said ironing-plate, a pivoted handle movable with said table, a hook or catch carried by said handle, and a pin in alignment with the

movement of said hook when said table is in alinement with said plate, and stops upon said handle adapted to limit the movement of said handle in both directions.

5 3. In a machine of the character described, the combination of an ironing-plate, an ironing-table movable to and from alinement with said ironing-plate, a pivoted handle movable with said table, a hook or catch carried by said handle and a pin in alinement with the movement of said hook when said table is in alinement with said plate, a spring connected to said handle tending to hold said hook in engagement with said pin, and stops upon 15 said handle adapted to limit the movement of said handle in both directions.

4. In a machine of the character described, the combination of an ironing-plate, an ironing-table movable to and from alinement with 20 said ironing-plate, a pivoted disk provided with a handle, movable with said table, a catch or hook carried by said disk and a pin in alinement with the movement of said catch when said table is in alinement with said plate, and 25 stops upon said disk adapted to limit the movement of said disk in both directions.

5. In a machine of the character described, the combination of an ironing-plate, an ironing-table movable to and from alinement with 30 said ironing-plate, a pivoted disk provided with a handle, movable with said table, a catch or hook carried by said disk and a pin in alinement with the movement of said catch when said table is in alinement with said plate, a 35 spring connected to said disk tending to hold said catch in engagement with said pin, and stops upon said disk adapted to limit the movement of said disk in both directions.

6. In a machine of the character described, 40 the combination of an ironing-plate, an ironing-table movable toward and from said ironing-plate, mechanism for controlling the extent of movement of said table in its movement toward said ironing-plate, mechanism 45 for controlling the extent of movement of said table in its movement away from said ironing-plate, the first-named mechanism being arranged to act more rapidly than the last-named mechanism.

50 7. In a machine of the character described, the combination of lifting mechanism for the ironing-table, comprising essentially a toggle mechanism, an internally-threaded block having a vertically-slotted extension, a rod projecting from a lever pivoted to the frame of the machine resting in said slot, a threaded shaft working in said threaded block and means to rotate said shaft in either direction and means to prevent longitudinal movement 55 of said shaft.

8. In a machine of the character described, the combination of lifting mechanism for the ironing-table comprising essentially a toggle mechanism, an internally-threaded block, a 60 shaft having a screw working therein, said block being connected to said toggle mechanism, tight and loose pulleys on said shaft, a

straight and a cross belt, a belt-shifter and shifter-rod, a stop in line of movement of a projection from said block and connections 70 between said stop and the belt-shifter rod adapted in the movement of the stop to shift one of the belts.

9. In a machine of the character described, the combination of lifting mechanism for the 75 ironing-table comprising essentially a toggle mechanism, an internally-threaded block, a shaft having a screw working therein, said block being connected to said toggle mechanism, tight and loose pulleys upon said shaft, 80 a straight and a cross belt, a belt-shifter and shifter-rod, a stop in line of movement of an intermediate point of the toggle-leg and connections between said stop and the shifter-rod adapted in the movement of the stop to 85 shift one of said belts.

10. In a machine of the character described, the combination of lifting mechanism for the ironing-table comprising essentially a toggle mechanism, an internally-threaded block, a 90 shaft having a screw working therein, said block being connected to said toggle mechanism, tight and loose pulleys upon said shaft, a straight and cross belt, a belt-shifter and shifter-rod, a stop in line of movement of a 95 projection from said block and connections between said stop and the belt-shifter rod adapted in the movement of the stop to shift the straight belt, a stop in line of movement of a toggle-leg and between the toggle-pivot 100 and the connection with the block, and connections between said stop and the shifter-rod adapted in the movement of the stop to shift the cross-belt.

11. In a machine of the character described, 105 in combination with an ironing-plate centrally disposed with reference to said machine, ironing-tables supported upon opposite sides of the machine and supported so as to swing under said ironing-plate, a vertically-movable 110 bar beneath said plate and extending across said machine, locking-pins on said bar on opposite sides of the center and locking mechanism on each table adapted to engage its corresponding pin when the corresponding table 115 is swung beneath the ironing-plate.

12. In a machine of the character described, 120 in combination with the toggle-legs, of a lifting-bar extending across the machine, and carried by said toggle-legs, and locking-pins 125 upon said bar on opposite sides of the center.

13. In a machine of the character described, 125 in combination with an ironing-plate and an ironing-table movable to and from said plate, of a scale secured to said plate and adapted to be in close proximity to and parallel with said table when said table is moved against said plate substantially as and for the purpose described.

14. In a machine of the character described, 130 the combination with an ironing-table, of lifting mechanism for said table adapted to elevate and depress said table, operating means for said lifting mechanism, mechanism adapt-

ed to cut off said operating means during the elevation of said table, mechanism adapted to cut off the operating means during the depression of said table, the first-mentioned cut-off mechanism acting more rapidly than the last-mentioned mechanism.

15. In a machine of the character described, the combination of lifting mechanism for the ironing-table, comprising a toggle mechanism, means for operating said toggle mechanism in both directions, mechanism operated by said toggle to control the operating means in both directions of the toggle movement, said mechanism operating in one direction of movement of the toggle, being at a different point on the toggle from that of the mechanism operating in the other direction.

16. In a machine of the character described, the combination of lifting mechanism for the ironing-table comprising a toggle mechanism, means for operating said toggle mechanism in both directions, mechanism operated by said toggle to control the operating means in both directions of the toggle movement, the mechanism operating in one direction of movement of the toggle, being at a different point on the toggle from that of the mechanism operating in the other direction, the controlling mechanism for the elevating stroke of the toggle being at a greater radial distance on the toggle than that of the controlling mechanism for the depressing stroke of the toggle.

17. In a machine of the character described, the combination of lifting mechanism for the

ironing-table comprising a toggle mechanism, means for operating said toggle mechanism in both directions, mechanism operated by said toggle to control the operating means in both directions of the toggle movement, said mechanism operating in one direction of movement of the toggle, being at a different point on the toggle from that of the mechanism operating in the other direction, and the controlling mechanism for the elevating stroke of the toggle being at the maximum radial point of the toggle.

18. In a machine of the character described, the combination of lifting mechanism for the ironing-table comprising essentially a toggle mechanism, an internally-threaded block, a shaft having a screw working therein, said block being connected to said toggle mechanism, tight and loose pulleys on said shaft, a straight and a cross belt, a belt-shifter and shifter-rod, a stop in line of movement of the toggle remote from its pivot-point and a stop in line of movement of the toggle between said last-mentioned stop and the toggle-pivot, said stops being on opposite sides of said toggle and connections between said stops and the belt-shifter.

In testimony of which invention I have hereunto set my hand, at Philadelphia, on this 16th day of December, 1902.

WILLIAM M. BARNES.
